By: B. Aniger att.

UNITED STATES PATENT OFFICE.

KARL VIKTOR RUDIN, OF STOCKHOLM, SWEDEN.

STEP-BY-STEP MECHANISM IN CALCULATING-MACHINES.

1,312,002.

Specification of Letters Patent. Patented Aug. 5, 1919.

Application filed March 18, 1918. Serial No. 223,232.

To all whom it may concern:

Be it known that I, KARL VIKTOR RUDIN, correspondent, subject of the King of Sweden, residing at Karduansmakaregatan 5 12, Stockholm, Sweden, have invented certain new and useful Improvements in Step - by - Step Mechanisms in Calculating-Machines, of which the following is a specification.

10 My invention relates to improvements in step-by-step mechanisms in calculating machines of that kind, wherein a usual locking-device for the movement of the sliding carriage is provided. Said locking-device 15 consists of a member, arranged on the carriage and movable up and down in a vertical plane, said member normally engaging in a horizontal row of grooves or notches in the frame of the machine.

20 In these machines the locking device can be actuated by hand and, at the same time is in any known way actuated by two projections or the like, arranged on the sliding carriage, which projections also engage with 25 a toothed bar or the like.

Machines of that type have been described in U. S. Patent No. 967,821.

My invention is essentially characterized thereby that each of the said projections 30 consists of two parts pivotally connected with each other and movable in the vertical plane, of which the one part is intended to be caused to engage with the toothed bar, when actuated in the said way.

35 An embodiment of my invention is illustrated in the accompanying drawing, wherein—

Figure 1 is a front view of a part of the sliding carriage, whereby the casing is partly broken away, in normal or resting position.

Fig. 2 shows the same but with the parts in that position, wherein the carriage has just been moved one step to the right, while

Fig. 3 is a vertical section of Fig. 1.

45 Fig. 4 is a detail plan, showing a portion of the frame provided with the series of notches 22 and also showing one of the members 4 engaged in one of said notches.

1 designates the casing of the sliding carriage. 2, 7 and 3, 8 designate the two projections, serving for the step-by-step movement of the sliding carriage to the right or to the left, said projections, of which 2, 7 are intended to be actuated when moving 55 the carriage to the right, and 3, 8 when moving same to the left, engaging in known way

in a member 4, movably up and down in a vertical plane and engaging as usual a horizontal row of grooves, notches or the like 22 on the frame of the machine. The projections 2, 7 respectively 3, 8 are journaled on the sliding-carriage, preferably on plates or disks 5 arranged on the same. Grooves or notches 9 respectively 10 are provided on the projections, suitably on the parts 7, 8 60 65 whereby said grooves are intended to catch the member 4 in order to move the same downward.

The projections 2, 7 respectively 3, 8 are actuated by springs, whereby each of the 70 two parts constituting one projection may be actuated by a spring or by a common spring. In the embodiment shown on the drawing the parts 2, 7 respectively 3, 8 are actuated each by a spring 16, 12 respectively 17, 13. 75 The said springs serve to move the projections back to their normal position. The movements of the projections are hereby limited by pins 14, 20 respectively 15, 21, which suitably lie in the way of the part 2 80 respectively 3.

There are further in a suitable place on the sliding carriage arranged projections 18, 19, which lie in the way for the projecting parts 7 respectively 8, which in their turn 85 serve to lock the same by means of one of the teeth on the bar 11, when the sliding-carriage has been moved one step.

The function of the device is as follows: 90 If for instance the carriage is to be moved one step to the right (Fig. 1 or 2), the projection 2 is actuated by hand and moved in the position, shown in Fig. 2. The projection 7 is hereby moved downward and the notch 9 is caused to catch the vertically 95 movable member 4, so as to move the outer end of said member downward and to release its inner end, engaging with the usual horizontal row of grooves or notches, whereby the carriage is permitted to move. The 100 carriage is thus under the pressure of the hand on the part 2 moved toward the right. Meanwhile the member 7 has been moved downward so long a way that the lower end of the same catches the space between 105 the teeth, being below. Hereby the engagement of the member 4 with the part 7 is released and the inner end of the member 4 is thus ready for a new engagement with the horizontal row of grooves or notches so as 110 to again lock the sliding carriage.

Hereby it can however often occur that if

the pressure on the part 2 is too strong the parts 4 and 7 are caused to jump over or to slide over more than one tooth on the bar and thus causing the carriage to move more than one step. In order to obviate this the projection or shoulder 18 has been placed in such a relation to the part 7 that this part, when the carriage has moved one step, is locked between the projection 18 and the tooth in question on the bar 11. It will hereby be impossible for the part 7, to slide over the tooth and full security will be obtained for that the carriage will not be moved more than one step at the time.

15 It may be remarked that the embodiment shown upon the drawing is taken only as an example and that the device may be modified in several ways.

I claim:—

20 1. A step-by-step mechanism in calculating machines including a framework provided with a horizontal row of notches, a sliding carriage capable of step-by-step movement, a locking device therefor including a member arranged upon the carriage, such member being movable in a vertical plane and normally engaging said notches on the framework of the machine, a pair of projections arranged on the sliding carriage, a toothed bar, such projections being adapted to engage therewith, each projection comprising two parts pivotally connected with each other, movable in a vertical plane, one of said parts being intended to be caused to engage with the toothed bar when actuated.

25 30 35

2. A step-by-step mechanism in calculating machines including a framework provided with a horizontal row of notches, a sliding carriage capable of step-by-step movement, a locking device therefor including a member arranged upon the carriage, such member being movable in a vertical

plane and normally engaging said notches on the framework of the machine, a pair of 45 projections arranged on the sliding carriage, a toothed bar, such projections being adapted to engage therewith, each projection comprising two parts pivotally connected with each other, movable in a vertical plane, one of said parts being intended to be caused to engage with the toothed bar when actuated, and springs having one of their ends secured to the framework, the opposite ends being secured to the projection 50 for normally withdrawing such projection out of engagement with the toothed bar.

3. A step-by-step mechanism in calculating machines including a framework provided with a horizontal row of notches, a sliding carriage capable of step-by-step movement, a locking device therefor including a member arranged upon the carriage, such member being movable in a vertical plane and normally engaging said notches on the framework of the machine, a pair of projections arranged on the sliding carriage, a toothed bar, such projections being adapted to engage therewith, 65 each projection comprising two parts pivotally connected with each other, movable in a vertical plane, one of said parts being intended to be caused to engage with the toothed bar when actuated, and stops secured to such carriage for preventing too great a movement of the projections so as to prevent their sliding over more than one notch at each actuation.

70 In testimony whereof I affix my signature 80 in presence of two witnesses.

KARL VIKTOR RUDIN.
